COMBINED BALLPOINT PEN AND LETTER
OPENER

Andrew Serin, Wildcat Road, Franklin, N.J.

Filed Nov. 2, 1959, Ser. No. 58,162

Term of patent 14 years

(Cl. D74—17)

Fig. 1 is a side elevational view of a combined ballpoint pen and letter opener showing my new design;

Fig. 2 is a side elevational view of the side opposite thereto;

Fig. 3 is an edge elevational view thereof looking in the direction of the arrow 3 on Fig. 1;

Fig. 4 is an edge elevational view looking in the direction of the arrow 4 on Fig. 1;

Fig. 5 is an enlarged cross-sectional view taken on line 5—5 of Fig. 1, and

Fig. 6 is an enlarged cross-sectional view taken on line 6—6 of Fig. 1.

I claim:

The ornamental design for a combined ballpoint pen and letter opener, as shown.
